CLAIM

The ornamental design for a screened tab for beverage cans, as shown and described.

DESCRIPTION

FIG. 1 is a top perspective view of a screened tab for beverage cans showing my new design;

FIG. 2 is a enlarged front elevational view thereof;

FIG. 3 is a enlarged left side elevational view thereof;

FIG. 4 is a enlarged right side elevational thereof; and,

FIG. 5 is a enlarged top plan view thereof.

The broken line showing of environmental structure is for illustrative purposes and forms no part of the claimed design.
